SHIPPING PACK

Application filed February 4, 1929. Serial No. 337,196.

The present invention involves both an improved package for the storage, delivery and shipment of such articles as plates, dishes or other food containers and an improved method of packaging such articles. For the purposes of this application we shall discuss our invention in its adaptation to the packaging of molded pulp articles which must be produced in large quantities and sold at a low price to fill the public demand for an inexpensive single use food container. It will be understood, however, that this treatment is purely illustrative and in no way limiting as the principles of our invention apply to the packaging of a wide variety of articles.

The packaging of such an article as a molded plate, dish, or the like, however, involves serious problems in handling, packing and shipping. These include the characteristic deformability of the individual articles, the more or less moisture absorbent nature of the materials used in their manufacture, ultimate shipping requirements as to quantity and size, protection against damage in handling, storage and equipment, and sanitary maintenance prior to use as food containers or dispensers.

It has heretofore been the practice in preparing such food containers for shipment to assemble a group of them in nested condition and to wrap around such group a sheet of wrapping paper, such wrapping sheet being held in place and the articles being longitudinally compressed to some extent by the application of one or more lengths of string or twine longitudinally about the package and over the ends thereof. The equipment for preparing such a package is shown in the Keyes Patent No. 921,256, dated May 11, 1909, and an improvement upon this machine is shown in the Williamson Patent No. 1,401,298, dated December 22, 1921. Both of these machines prepare a package in which the twine is tied on the outside of the wrapping paper, the wrapping paper affording no material protection to the ends of the package and allowing dirt and other foreign matter to reach the food containers both through the ends of the package between the containers and the wrapper and also along the sides

of the package where the two ends of the circumferentially applied wrapping sheet meet each other. Moreover, the edge of the wrapping sheet is exposed and hence is frequently torn during shipment or handling thus exposing part of the sides of the package lengthwise to entrance of dust and dirt.

In the effort to avoid the disadvantage of such a package it has been proposed to first pass the string or twine longitudinally about the group of nested articles, then enclose the group in the paper wrapping sheet and finally apply sealing discs to the ends of the group. The twine, however, forms ridges between the food containers and the wrapping paper and to some extent damages the containers themselves particularly when the twine is drawn tightly about them. Such ridges moreover make the wrapper more liable to damage than where a smooth uninterrupted external surface is presented.

Our present invention aims to overcome the disadvantages of such prior packages and involves certain improvements in both packaging methods and the package itself to the end that we may provide a storage, delivery and shipping package which is completely sealed against the ingress of dust, dirt and other foreign matter so that the food containers may be delivered to the points of use in a clean, sanitary condition and without danger of contamination in any way by contact with foreign matter during storage or shipment.

In carrying out our invention we first nest and compress the desired number of food containers into a group or bundle and then wrap a sheet of wrapping paper or other covering material circumferentially about the group. We next apply a strip of sealing tape or other suitable material over the joint or lap between the edges of the covering sheet. This strip of sealing tape extends from end to end of the package and completely closes such joint or lap against ingress of dust or dirt. The ends of the sealing strip are passed around the ends of the package and sealed down to the wrapping sheet on the side opposite the lap or joint. This sealing tape serves the dual purpose of sealing the ends of the wrap-

- ping sheet together and of holding the package in shape for subsequent application of the end sealing heads thus making a dust and dirt proof seal for the wrapper. The package is then subjected to a second operation wherein gummed or other suitably prepared heads or sealing discs are placed adjacent to the ends of the package and are folded over into contact with the wrapper to which they are sealed down in dust proof relation whereby tightly to close both ends of the package. In our package therefore we obtain a completeness of seal not possible in previous packages in that the lap or joint of the covering sheet is completely closed from end to end by the sealing tape and the ends of the package are completely closed by the end sealing discs. In such a package the use of string or twine and the resultant danger of damaging the edges of the articles in the application of the twine as well as the formation of the objectionable ridges beneath the wrapping sheet, due to the physical presence of the twine is avoided. Our package is a sealed, wrapped package in which the wrapper surface is smooth and even and hence is not apt to be broken or torn during handling or shipment due to the formation of the ridges caused by the underlying twine.
- 20 In the accompanying drawings we have attempted to illustrate somewhat diagrammatically the steps of our method and the characteristic resultant packs produced thereby. In these drawings:
- 25 Fig. I is a section through a stack of plates before compaction.
- Fig. II a similar section through such a stack after compaction.
- Fig. III a view of the initial step in wrapping the stack.
- 30 Fig. IV shows the stack wrapped and sealed at the lap or joint of the wrapper ends.
- Fig. V a diagrammatic indication of the end sealing.
- 35 Fig. VI shows the completed pack unit with end heads sealed down over the wrapper.
- Fig. VII a plural unit pack partly broken away to illustrate its interior, and
- 40 Fig. VIII one of the plural units removed.
- 45 Referring to Fig. I it will be noted that the plates P in the stack S are relatively loosely nested within one another before compaction. For purposes of illustration we have shown one or more of the plates at P¹ at one end (the right hand end) of the stack in this figure as reversed with respect to the main assemblage. This presents convex heads at both ends of the completed package, but it will be understood that all of the plates may be nested alike if desired.
- 50 After assembly in either of the nested conditions just indicated the stack is subjected to a longitudinal compression, as indicated in Fig. II by the arrows A—A, under which the

stack is compacted and the plates brought to substantially uniform alignment.

This compacting, furthermore, gives to the stack a resistance to rough handling in transportation and makes it possible with a comparatively thin envelope or wrapper W to have such packs go through shipment without damage. Furthermore, by the close packing and the sealing which we will next describe, it is possible to have a perfectly sanitary pack which is of course very important where the articles contained are intended for food containers and the like.

In practice while the stack is held under end pressure, as indicated at a the covering sheet W is brought about the stack, shown in Fig. III, and the overlapped edge of the sheet W sealed as by a strip of adhesive tape T, Fig. IV. The tape T is brought across the ends of the wrapped stack and sealed down on the covering sheet at the side opposite the lap or joint thereof as indicated at T'.

The strip T both seals this lap or joint against ingress of dirt and dust and holds the group of plates in shape for subsequent application of the end sealing heads or discs. In the next step, shown in Fig. V, the pack thus prepared, has a pair of end sealing discs D of paper or like material brought up against the stack and under end pressure again, as indicated by the arrows A. The edges of the discs D, which are preferably slotted as at d, are then forced over the ends of the stack and firmly cemented thereto by the adhesive with which the disc is coated. This now converts the compacted and wrapped stack into a double sealed package viz, the seal afforded by the tape T at the lap or joint of the wrapper ends and that afforded at the ends of the pack by the end sealing discs D. So sealed and wrapped the package is practically dirt and dust proof. (See Fig. VI.)

The packs may contain of any size or number of articles, such packs being in one characteristic form of one hundred plates. Instead, however, of making the pack a single unit, it may in one form of our invention be made up as a plural unit as illustrated in Fig. VII. In this figure we have illustrated five small packs indicated by the reference letter U. These sub-units U are illustrated in Fig. VIII and are generally packed under the same method before described, with the exception that we preferably do not reverse an end plate as indicated at P¹ in Fig. II, but wrap and end seal the stack of plates so that the unit U instead of being convex at both ends, is convex at one end and concaved at the other. In this way the plural units U interengage and articulate so that they are held in alignment and cannot be laterally dislodged by any ordinary handling. We, however, preferably reverse one end unit as indi-

cated at U¹ in Fig. VII, so as to give a convexity to both ends of the multiple unit. In such 5 multiple unit pack the exterior wrapper W¹ is applied and sealed at its lap or joint as at T² by the same method as with the unitary pack, and the end discs D¹ are put on in the same way.

Such a multiple unit is of great convenience where the enclosed ware is to be retained for private use, as for example, picnic 10 plates. The dealer is able by simple breaking the outer sheet W¹ of such a plural pack to hand to the customer a sealed unit U of say fifty plates, which may be kept sealed by 15 the customer until they are desired for use. This is not only a great convenience in handling, but gives the individual user a sealed and sanitary pack which may be transported and handled without danger of having the 20 contents contaminated.

For greater convenience in opening such a multiple unit pack, we may provide a rip string S (Fig. VII) for cutting the outer wrapper W¹. Such string may have one end 25 secured beneath the sealing tape T² for S¹ secured, beneath the sealing tape T² for the lap joint of this wrapper. The string is then carried towards the opposite end of the wrapper W¹, being staggered to avoid the tape T² and laps of the wrapper and thus to 30 reduce the number of thicknesses of material which must be torn through. The string is exposed at its free end as a grasping portion S².

Preferably also we print directly on the 35 outer faces of the end sealing discs D or D¹ the usual identifying data as to the contents of the package. This avoids the necessity for applying a separate label on the side of the wrapper, as has heretofore been the practice, 40 and makes far greater convenience in storing and handling the packages for storage and shipment.

Our method may be practiced by hand or 45 by any convenient means or mechanism and the packs as above suggested may be of any desired form and the wrapping elements may be varied, although the combination shown is one of great practical value and of demonstrated efficiency.

Similarly we may use other materials than 50 gummed tape, as for example, a simple band of adhesive, for sealing the lap or joint of the wrapper and such adhesive could also be used for sealing down the end discs. All 55 such departures in methods and materials are to be regarded as within the spirit and scope of our invention if within the limits of the appended claims.

What we therefore claim and desire to secure by Letters Patent is:

1. A sealed wrapped package, consisting of a longitudinally compressible stack of nested articles of fibre ware, a wrapping sheet of sufficient strength to hold said articles in alinement tightly rolled about said stack, a

strip of sealing tape securing the free edge of said wrapping sheet to the body thereof and having its ends extended diametrically over the ends of the stack and secured to the body of the sheet after compression has been applied to the stack, and end sealing members applied over the ends of the wrapping sheet and secured thereto. 70

2. A sealed wrapped package, consisting of a longitudinally compressible stack of nested articles of fibre ware, a wrapping sheet of sufficient strength to hold the articles in alinement tightly rolled about said stack, a tie member disposed longitudinally of the stack and over the ends thereof after compression has been applied to the stack for holding the stack compressed, and end sealing members applied over the ends of the wrapping sheet and sealed thereto. 75

3. A sealed wrapped package, consisting of a longitudinally compressible stack of nested articles of fibre ware disposed in interfacially contacting relation to each other and axially expansible upon release of the longitudinal compression, a wrapping sheet of sufficient strength to hold said articles in alinement tightly rolled about said stack, said wrapper having a longitudinal edge overlapped upon the underlying body portion of the sheet, a closure strip applied over said overlapped edge of the wrapper after the stack has been longitudinally compressed and sealing said wrapper around the stack as a circumferentially confining open-ended tubular stack envelopment, and end sealing members applied over the endmost articles of the stack and sealed to the end portions of the wrapper in closing relation thereto after said sealing strip has been applied, said end sealing members and strip cooperating with the wrapper 95 to form thereof a substantially dust-tight protective enclosure which completely envelopes the stack and is sealed at its ends and along one longitudinal edge as a completely enclosing stack envelopment effective both to restrain the stack against axial expansion upon release of the longitudinal compression and to prevent the entrance of foreign matter into the stack. 100

4. A sealed wrapped package, consisting of a stack of nested articles of fibre ware disposed in interfacially contacting relation to each other and compressed longitudinally, a wrapping sheet of sufficient strength to hold said articles in alinement tightly rolled about said stack, said wrapper having a longitudinal edge overlapped upon and sealed to the underlying body portion of the sheet after the stack has been longitudinally compressed and sealing said wrapper around the stack as a circumferentially confining open-ended tubular stack envelopment, and end sealing members applied over the endmost articles of the stack and sealed to the end portions of the wrapper in closing relation thereto 110 105 115

after said wrapper has been sealed around said stack, said end sealing members cooperating with the wrapper to form thereof a substantially dust-tight protective enclosure which completely envelopes the stack and is sealed at its ends and along one longitudinal edge as a completely enclosing stack envelopment effective both to restrain the individual articles in stack against separation upon release of the longitudinal compression and to prevent the entrance of foreign matter into the stack.
